UNITED STATES PATENT OFFICE.

JOHN H. SARGENT, OF SOUTH BETHLEHEM, PENNSYLVANIA, ASSIGNOR TO WILLIAM HENRY KREIS, OF SOUTH BETHLEHEM, PENNSYLVANIA.

SEWING-THIMBLE.

1,175,180.

Specification of Letters Patent. Patented Mar. 14, 1916.

Application filed April 10, 1915. Serial No. 20,456.

To all whom it may concern:

Be it known that I, JOHN H. SARGENT, a citizen of the United States, residing at South Bethlehem, in the county of Northampton and State of Pennsylvania, have invented certain new and useful Improvements in Sewing-Thimbles; and I do hereby declare the following to be a full, clear, and exact description of the invention, such 10 as will enable others skilled in the art to which it appertains to make and use the same, reference being had to the accompanying drawings, and to the letters and figures of reference marked thereon, which form a 15 part of this specification.

This invention relates to new and useful improvements in sewing thimbles and the object of the invention is to produce a simple and efficient device of this nature so arranged 20 as to protect the nail at the end of the finger and consists essentially in the provision of a cushion of rubber or other suitable material placed within the thimble and preventing the end of the finger coming in 25 direct contact with the concaved end of the thimble when in use.

More specifically, the present invention consists, in connection with a thimble, of a circular disk of rubber or resilient material, 30 shaped upon one face to conform to the concaved end of the thimble upon which it is mounted, and provided with a beveled edge forming a means for the reception of the nail of the finger of a person, thus protecting 35 the nail when pressure is applied to the cushion in the use of the thimble.

My invention is illustrated in the accompanying drawings, in which:

Figure 1 is a longitudinal sectional view 40 through the thimble. Fig. 2 is a transverse sectional view through the thimble. Fig. 3 is a detail of the cushion.

Reference now being had to the details of the drawings by letter, A designates a hard 45 shell thimble of the usual construction having the concaved inner end, and B is a cir-

cular outlined yielding filler of suitable material and which has a convexed surface C adapted to conform to and contact with the inner concaved end of the thimble. Said 50 filler is provided with a circumferential bevel D, the inner marginal edge of which terminates at the outer portion of the concaved part of the thimble, and an annular space E is provided for the reception of the 55 projecting end of a finger nail.

When the cushion is applied to the thimble in the manner shown and pressure is applied in the act of forcing a needle through the material, it will be noted that the end of 60 the finger will be prevented from coming in contact with the tapering surface of the thimble at the inner concaved end and which is frequently the cause of making the fingers sensitive and otherwise injuring the 65 same but, by the provision of the cushion beveled as shown, pressure applied to the thimble will allow the nail to enter the space about the beveled part of the disk and the cushion will receive the thrust against 70 the end of the finger, thus preventing the finger from being injured as well as protecting the finger nail.

What I claim to be new is:—

A thimble comprising a hard shell and 75 having its inner end concaved, a removable circular-outlined yielding filler having a convexed end conforming to and in contact with said concaved end, the circumferential wall of the filler having a beveled portion, 80 the inner marginal edge of which terminates at the outer portion of said concaved part of the thimble, thus allowing an annular space between the filler and the wall of the thimble for the finger nail of the person on 85 whose finger the thimble is placed.

In testimony whereof I hereunto affix my signature in presence of two witnesses.

JOHN H. SARGENT.

Witnesses:

A. L. HOUGH,

FRANKLIN H. HOUGH.
